UNITED STATES PATENT OFFICE.

CHARLES N. PETESCH, OF CHICAGO, ILLINOIS.

HORSE-POWER RECORDER.

1,077,637.

Specification of Letters Patent.

Patented Nov. 4, 1913.

Application filed June 8, 1913. Serial No. 772,669.

To all whom it may concern:

Be it known that I, CHARLES N. PETESCH, a citizen of the United States, residing at Chicago, in the county of Cook and State 5 of Illinois, have invented a new and useful Improvement in Horse-Power Recorders, of which the following is a specification.

My invention relates to an improvement in the class of devices used as attachments 10 on engines for recording the horse-power by tracing it on a suitable dial with a stylus connected with the engine-governor to be actuated thereby.

In the accompanying drawings, Figure 1 15 is a broken view in elevation of an engine of the Corliss type showing my improved device attached thereto; Fig. 2 is an enlarged view showing the recorder in front elevation; Fig. 3 shows the same by a broken 20 view in rear elevation; Fig. 4 is an enlarged broken view in sectional elevation of the device, the section being taken on line 4, Fig. 2; Fig. 5 is an enlarged section on line 5, Fig. 2; Fig. 6 is a section on line 6, Fig. 4; 25 Fig. 7 is a section on line 7, Fig. 6, and Fig. 8 is a section on line 8, Fig. 7.

A circular clock-casing 9, shown to be provided with a glass-covered door 10, hinged at 11, contains the works of a clock, 30 only the hour-hand arbor 12 of which is shown carrying a lower disk 13 (Fig. 4) and having pinned to its outer end a sleeve 14 about which seats a thimble 15 provided about its inner end with a disk 16 and fastened to the sleeve by a thumb-screw 17. A circular plate 18, preferably of fiber-board, surrounds the arbor at the base of the sleeve 14 and forms a backing for a dial 19, preferably of paper; and the circular 40 plate and clock-facing dial are clamped between the disks 13 and 16 to rotate with the arbor. The disk may be marked with a plurality of uniformly-spaced concentric circles, as shown in Fig. 2, and is numbered about 45 the outermost circle from 1 to 12 in two successive series to divide the hours from noon and from midnight, the numbers being uniformly spaced apart. A line, which is non-radial for the reason hereinafter explained, 50 extends from each hour-indicating number to the innermost circle; and the circles are marked, from the innermost outwardly, 0 to 6 along each of several of the non-radial lines, as at each quarter of the circle, which

is sufficient. These numbers (from 0 to 6) 55 denote, each, one-hundred horse-power.

On the back of the casing 9, where clock-winding arbors are shown to be provided at 20 and 21 (Fig. 3), is rigidly secured to extend diametrically across it, a rectangular 60 bar 22 forming part of a bracket device and containing a rear elongated slot 23, the bar expanding at its forward end into a rectangular bracket-plate 24 from the lower inner corner of which depends an ear 25 65 having rigidly fastened to it a sustaining-post 26. The bracket contains a lower elongated guide-slot 27 alining with the slot 23 and extending some distance into the bar 22, and, parallel therewith, a shorter guide-slot 70 28; and centrally on the forward end of the back of the bracket-plate is provided a guide-loop 29. The bar 22 forms a guide for the movement of the casing 9, as and for the purpose hereinafter described, by being confined between a correspondingly-shaped inner strip 30 directly on the bottom of the casing, and a similar outer strip 31 having, on its forward end, an offset tongue 32 working at its advance-end through the loop 29, 80 and having a guide-lug shown on its back, working in the slot 28. The strips 30 and 31 are rigidly secured together and to the back of the clock-casing by bolts 33' passing through them and through guide-blocks 33, 85 33' reciprocably confined in the slots 23 and 27.

A rod 34, shown hollow and of rectangular cross-section, works through an opening 35 in a part of the sheet-metal casing somewhat 90 in advance of the plane of the dial, where it is shown to be reinforced across its periphery by a relatively-heavy metal strip 36 fastened in place by screws. On the inner end of this rod is carried a stylus-device 37 95 (Figs. 6, 7 and 8) for marking the face of the dial 19. This device is on a stem 38 insertible into the inner end of the rod 34 and carrying on its rear end, to extend transversely thereof, a bearing-plate 39. To the 100 outer face of this bearing-plate is rigidly fastened, to cross it, a tubular holder 40 for a stylus, in the preferred form of a lead-pencil 41, the holder being slotted at 42 (Fig. 7), along one side and perforated at its 105 inner end for the pencil-point to protrude through it; and the pencil is carried in a sleeve 43 (Fig. 8) having a lug 44 extend-

ing from it through the slot, and against which a follower-finger 45 bears. The finger 45 is pivoted at one end on the bearing-plate 39, near one end of the latter, the pivot-pin 5 46, which carries the finger, being journaled in the bearing-plate and carrying, at the side thereof opposite that on which the follower-finger extends, a yoke 47, in the slot of which works an adjusting-screw 48' for 10 a link 48 having one end of a spiral spring 49 connected with it and passing at its opposite end into a sleeve 50 on a clip 51 secured to the plate 39 and having a slotted end at 52. A thumb-screw bolt 53 works in 15 the slot 52 and has the spring 49 connected with it for tensioning the spring, by moving and setting the bolt in the slot, to regulate the pressure of the follower-finger against the pencil-sleeve lug 44 and thus regulate 20 the pressure of the pencil against the dial.

The rod 34 works guidingly at its forward end through the upper end of a post 54 rigidly extending from the face of the bracket-plate 24 at the outer end of the slot 27, and 25 it also works through a guide loop 55 extending from a cross-head 56 secured on the upper end of a post 57 rigidly projecting from the face of the bracket-plate near its lower edge and adjacent to the slot 27. The 30 rod carries, to reciprocate with it, at a point between the post 54 and guide-loop 55, an arm 58, through which, near its outer end, the rod passes and is secured thereto by a set-screw 58' working against it in the outer 35 end of the finger. The arm carries on its end at the slot 27 an index-finger 59 formed of a pair of rectangular plates fastened together and to the end of the arm 58 to embrace the opposite sides of the slot and reciprocate along it, the front plate, or member 40 of the index-finger, which forms the index-finger proper, moving along the adjacent edge of a scale-plate 60 secured to the face of the bracket-plate 24 between its slots 45 27 and 23, and marked off with transverse lines equally spaced apart, denoting hundred horse-powers, with intermediate uniformly-spaced short lines denoting twenty-five horse-powers. The hundred horse-power 50 lines on the plate 60, between which six spaces are shown, should be, at least approximately, twice the distance apart of the spacings between the horse-power indicating numbers along the non-radial lines on 55 the dial. A lever 61, fulcrumed between its ends at 62 (Fig. 3) on the back of the bracket 24, has a link-connection 63 at its lower end with the rear plate of the index-finger 59, a link-connection 64 midway between its ends with a rigid arm 65 extending 60 on the tongue transversely thereof, and a link-connection 66 at its upper end with an operating-lever 67 fulcrumed at its lower end, at 68, to the back of the bracket-plate. 65 To attach my improved device in proper

relation to the engine illustrated in Fig. 1, a bracket 69 is shown on an end of the engine-frame, into which the sustaining-post 26 is screwed. The operating-lever 67 is connected by a link 70 with a rod 71 extending from 70 a boss 72 on an oscillatory shaft 73 having the ordinary connections, as shown, with the governor and other parts of the Corliss type of engine illustrated. As these connections and their manner of operation are 75 well-known to those skilled in the art, and form no part of my present invention, explanation thereof herein would be superfluous.

In applying my improved device to its operative position, the parts are so adjusted as to remain stationary with the pencil at zero on the dial and the index-finger at zero on the scale 60, until the engine is loaded. Then the oscillations of the rod 71 80 actuate the lever 67 to move the rod 34 and thus actuate the pencil against the dial and the index-finger along the outer, relatively magnified scale. The works of the clock 85 revolve the dial with the hour-hand arbor, 90 and the movements of the rod 34 with the variations in the load on the engine, cause the pencil to trace these variations, to indicate the horse-power, on the dial, which shows the time of night and day to which 95 the tracing applies. The non-radial lines are so arranged correspondingly on the dial as to cause each, when it comes into line with the stylus 41, to extend parallel with the path of movement of the latter, thereby 100 more accurately to indicate the horse-power on the dial. Each longitudinal movement of the rod 34 moves the stylus and the index-finger 59 correspondingly; but by the link-connection 66 of the operating lever with 105 the one end of the lever 61 and of the connection of the opposite end of the last-named lever with the index-finger 59, the latter is moved the length of the full throw of that lever, while the link-connection 64 110 of the tongue 32 being with the lever 61 midway between its ends, the movement of the casing is only one-half the extent of that of the index-finger. The readings on the scale 60 being thus twice as large as the 115 comparatively diminutive tracings on the dial, may be much the more easily inspected. As will be seen, the movement, by moving the casing, of the dial across the stylus diminishes the corresponding movement of the latter by one half (according to the present arrangement, though the arrangement may provide different proportions without departure from my invention), and thus relatively doubles that of the index-finger. 120

I realize that considerable variation is possible in the details of construction thus specifically shown and described, and I do not intend by illustrating a single, specific or preferred embodiment of my invention to 130

be limited thereto; my intention being in the following claims to claim protection upon all the novelty there may be in my invention as broadly as the state of the art 5 will permit.

What I claim as new and desire to secure by Letters Patent is:

1. In a horse-power recorder, the combination of a clock having a rotatable horse-power indicating dial-face, a bracket-device 10 on which the clock is reciprocably supported, a rod reciprocably supported on the bracket-device to work at one end across said face, a stylus-device on said end of the rod, a scale on the bracket-device, an index-finger connected with the reciprocating rod to coöperate with said scale, an operating-lever, and lever and link-connections of the 15 operating-lever with said finger and clock for moving them together, with a relatively-greater movement of said finger along the scale.

2. In a horse-power recorder, the combination of a clock provided with a rotatable dial-face having non-radial lines thereon, with horse-power denoting characters spaced along one or more of said lines, a bracket-device 20 on which the clock is reciprocably supported, a rod reciprocably supported on the bracket-device to work at one end across said face, a stylus-device on said end of the rod having the stylus thereon movable, by the movement of said rod, in a path parallel with the non-radial line brought coincident 25 therewith in the rotation of the dial-face, a scale on the bracket-device, an index-finger connected with the reciprocating rod to co-operate with said scale, an operating-lever, and lever and link connections of the operating-lever with said finger and clock for 30 moving them together, with a relatively-greater movement of said finger along the scale.

3. In a horse-power recorder, the combination of a clock having a rotatable horse-power indicating dial-face, a slotted bracket-device having a bar on which the clock is supported to be reciprocated, a rod reciprocably supported on the bracket-device to 35 work at one end across said face, a stylus-device on said end of the rod, a scale extending along a slot in the bracket-device, an index-finger reciprocably confined in said slot

and connected with the reciprocating rod to move therewith, an operating-lever, and lever and link connections of the operating-lever with said finger and clock for moving them together, with a relatively-greater movement of said finger along the scale. 55

4. In a horse-power recorder, the combination of a clock having a rotatable horse-power indicating dial-face, a bracket-plate having a slotted bar extending from it across the clock-base, a strip extending along said bar, bolted to said base through the bar-slots and having a tongue extending guidedly along said plate, a rod reciprocably supported on said plate to work at one end across said face, a stylus-device on said end of the rod, a scale on the bracket-device, an index-finger connected with the reciprocating rod to coöperate with said scale, an operating lever, and lever and link connections of the operating lever with said finger and tongue for moving the finger and clock together, with a relatively-greater movement 65 of said finger along the scale. 70

5. In a horse-power recorder, the combination of a clock having a rotatable horse-power indicating dial-face, a slotted bracket-device, by which the recorder is supported in operative position, and having a plate with a slotted bar extending from it across the clock-base, a pair of strips embracing said bar and bolted through its slots to said base, the outermost strip having an off-set tongue guided along a slot in said plate, posts extending from the face of said plate, a rod reciprocably supported by said posts to work at one end across the dial-face, a stylus-device on said end of the rod, a scale 80 extending along a second slot in said plate, an arm on said rod, an index-finger on said arm reciprocably confined in said second slot, an operating-lever fulcrumed at one 85 end on said plate, and a lever fulcrumed between its ends on said plate and linked at its opposite ends respectively to said operating-lever and the index-finger and between its ends to said tongue, for the purpose set 90 95 forth. 100

CHARLES N. PETESCH.

In presence of—

L. HEISLAR,
A. FISCHER.
